JAW PULLER

Oscar C. Schmidt, Cincinnati, Ohio, assignor to
The Cincinnati Butchers' Supply Company,
Cincinnati, Ohio, a corporation of Ohio

Application July 13, 1938, Serial No. 219,001

9 Claims. (Cl. 17—1)

My invention relates to jaw pullers, such as used in the butchering industry, for separating the jaws from the skulls of animals, and is exemplified as a jaw puller for hogs.

It is the object of my invention to provide a new and improved jaw puller of simple construction, extreme accessibility and capable of ready adjustment; further, to provide a jaw puller in which the jaw pulling means and the feeding means contacting the head and the jaw to feed the same are located in overhanging relation or projecting outwardly from the supporting frame so as to make the feeding and operating means extremely accessible and for ease of feeding manipulation of the heads being fed; and, further, to so mount the feeding and jaw pulling means that the head being operated on may be moved from left to right or from right to left and the jaw pulling devices may project upwardly or downwardly or laterally for convenience of association with other apparatus, for instance, a snout puller in connection with which the jaw puller operates, and with the stations of operatives, such as trimmers, performing other operations, and arranged, for instance, about a table, upon which the heads or the portions thereof and the trimmed meats, fats, skins, gristles, bones and the like, resulting from operations on the head, are supported either directly or in suitable containers.

My invention consists in novel means for accomplishing these objects; further, in mounting the operating parts which operate upon the head of the carcass so as to project in overhanging relation from their supporting frame for freedom of access thereto and for ease of feeding manipulation, and so that the parts may be readily cleaned and maintained in sanitary condition, which is an important factor in this industry; further, in providing new and improved driving means and arrangement thereof in relation to the feeding means for the heads being operated on; further, in a new and improved means for adjustably positioning the stripper for stripping the jaws from the feeding means; and, further, in providing a new and improved jaw pulling horn and new and improved means for adjustably positioning the same with relation to the frame and the direction of feeding movement of the head.

The invention will be further readily understood from the following description and claims, and from the drawings, in which latter:

Fig. 1 is a front elevation of my improved device.

Fig. 2 is a side elevation thereof, partly broken away.

Fig. 3 is a detail view of a portion of the feeding means, taken on the line 3—3 of Fig. 2.

Fig. 4 is a vertical section of my improved device, taken on the irregular line 4—4 of Fig. 2, and partly broken away.

Fig. 5 is a cross-section of a portion of the driving means, taken on the line 5—5 of Fig. 1, and partly broken away.

Fig. 6 is a cross-section, taken in the plane of the line 6—6 of Fig. 4, partly broken away, exemplifying the feeding means.

Fig. 7 is a front view of the outer shield or wall for the feeding space.

Figs. 8 to 15, inclusive, are elevations of my improved device, showing various ways of mounting the same, so as to adapt the same to varying circumstances in connection with operations upon the head and its parts, and showing the various ways in which the parts of the device coacting with the head may be positioned by the adjusting means provided, to place the operating parts in positions for greatest convenience of operation upon the head and its parts.

A frame 21 comprises side members 22, 23, connected at their upper ends by a plate 24, which forms a top for the frame, and has flanges 25 received in rabbets 26 of the side members, the plate being fastened to inwardly extending flanges 27 of the side members by bolts and nuts 28. Cross bars 29 are connected with the lower portions of the side members by bolts and nuts 30.

The frame is arranged to be secured to extend in various directions from supports for purposes hereinafter described. Such securing means may be screws 34, which pass through holes 33 in feet 35 of the frame and are threaded into the top 36 of a table 37 or into such other support for the frame as may be desirable, for securing the device firmly to the table or other support. The table is usually provided with a rust-proof sheet 38 on which the manual operations on the head and its parts take place.

The top of the frame has a pedestal 41 extending therefrom. The pedestal is shown as having the operating parts for the head and the jaw mounted thereon so as to support the same from the frame. The pedestal is shown as comprising a plate 42 which serves as an inner shield or wall for a feeding space 43 of my improved device. The margin of this wall is preferably substantially annular and is preferably provided with a marginal strengthening flange 44, which merges into brackets 45 at the base of the

lateral edges of the wall adjacent to and connecting with the top 24 of the frame.

The pedestal is provided with a bearing 48 near its middle and extending perpendicular thereto, the inner portion of the bearing being connected with the pedestal by ribs 49 for strengthening the structure. A feed shaft 51 suitably driven is rotatable in the bearing and extends through the pedestal. A feed wheel 52 10 is secured to said feed shaft as by a key 53 and set bolt 54, and forms a feed wheel for the carcass head. It operates in the feeding space 43 at the side of the pedestal and preferably overhangs laterally outward from the frame. The 15 feed wheel has an outer peripheral portion 57 which coacts with the jaw portion of the carcass head for positioning the latter, and with feed fingers 58 which are arranged about the outer periphery of the feed wheel, being preferably 20 equally spaced thereabout.

The feed fingers are located in sockets 59 in said feed wheel and are secured in said sockets by taper pins 60 in registering taper holes in the wall of said socket and the base of said 25 finger. The fingers are of greater width than thickness, being provided with side rabbets 62 for forming flat faces at their sides, the greater width of the fingers extending in the directions of the feed to resist the great pulling strains 30 upon the fingers during the feeding of the heads and to present as little crushing area to the jaws consistent with their pulling stresses, to avoid as much crushing of the jaw as possible in the pulling operation.

35 A horn 65 is provided, along which the carcass head is fed in the feeding or pulling operation. It is provided with flanges 66 at its respective sides, bolts 67 passing through the flange at one of its sides and through the supporting wall 42, 40 nuts 68 being threaded over the threaded ends of said bolts for clamping the horn to said supporting wall or pedestal. The horn is provided with a track 69, along which the jaw side of the head is fed, the major portion of this track having 45 a curvature presented to the feed wheel which is substantially concentric with the outer periphery of the feed wheel or path of the feed fingers, and coacting with the feed fingers in their paths along the track for pulling the jaw 50 along said track.

The horn has an entering portion 70 substantially round in cross-section and curved outwardly from the major portion of the track recedingly from the feed wheel. This entering portion 55 has a reduced outer end 71 to form a receiving end of said horn, providing for ready reception of the mouth of the carcass head thereabout, it being understood that the mouth end of the head is pushed about the receiving or entering end of 60 the horn, with the jaw or under side of the head presented toward the feed wheel, and the normally upper or skull side of the head presented away from the feed wheel so that the horn acts on the head between the jaw and the skull.

65 The horn is provided with outwardly presented tracks 72 which spread laterally at both sides of the longitudinal middle portion of the horn and also diverge from the feed wheel and the track nearest to the feed wheel, forming a three point 70 wedge which spreads laterally and angularly with relation to the feed wheel for relatively spreading the jaw and the skull, and, due to the pulling action of the feed fingers and feed wheel upon the jaw portion of the head, relatively separates the skull portion and the jaw portion of

the head, so that the jaw portion moves along the track 69 adjacent to the feed wheel and the skull portion moves along the tracks 72 spaced therefrom, said tracks forming a wedge therebetween and causing separation between the jaw 5 portion and the skull portion of the carcass head.

The jaw is U-shaped, having a front or bridge end and sides, and, after separation, the front end rides upon the track 69 adjacent to the feed wheel, and the sides of the jaw arrange themselves at the sides of said track 69, the feed wheel feeding the jaws along said track adjacent thereto off the outfeeding end 73 of said track, for permitting the jaws to fall upon the table or be led to such other point as desired for further 15 operation thereon. The outfeeding end of said track may have a delivery rod 74 connected therewith, as by providing said delivery or outfeeding end with a slot 75 and the adjacent end of the rod with a tongue 76 received in said slot, 20 a taper pin 77, for instance, located in registering taper holes in the walls of said slot and in the tongue, connecting the same in manner so that the severed jaws may be readily fed and guided therealong.

25 A stripper 81 has stripper fingers 82, which project toward the feed wheel, and are arranged at the respective sides thereof and about the feed fingers in such manner that the separated jaws are positively stripped from the feed wheel and the feed fingers. The contact faces 83 of the stripper fingers slant toward the outer periphery of the feed wheel and coat with the jaws, being arranged preferably on a curve tangent to the approaching portion of the outer periphery of 30 the feed wheel and inclined toward the oncoming feed finger so as to readily release the severed jaw from the feed wheel and the finger. The base 84 of the stripper is provided with flanges 85 at the respective sides thereof, one of which 35 is secured to the pedestal or supporting wall 42 by clamping bolts 86 and nuts threaded thereover.

A shield 91 forms an outer wall for the feeding space 43 in which the feed wheel and its fingers rotate. This shield or outer wall may also form a strengthening means for the operating portion of my improved device by being clamped to the other of the flanges 66 of the horn by clamping bolts 92 and nuts threaded 40 thereover and to the other of the flanges 85 of the stripper by bolts 93 and nuts threaded 45 thereover. The peripheral portion of the outer shield or wall may be connected (Fig. 4) with the pedestal or inner wall by connecting bolts 94 and nuts 95 threaded thereto, spacing tubes 96 50 being located about said bolts for properly spacing said walls.

Such connecting bolts, nuts and spacing tubes are located at the top portion of the outer shield or wall, in the various positions assumed by the frame, as hereinafter explained, and at the side of said outer shield or wall opposite to the side at which the stripper is located, in such various positions of the frame, to stiffen the structure, as 55 see Figs. 8 to 15 inclusive.

The driving means exemplified comprise an electric motor 101, which is preferably a reversible electric motor, or an electric motor in which the direction of rotation of the rotor may 60 be reversed for rotating the feed wheel in opposite directions for the purposes hereinafter described. The motor is shown adjustable for adjusting the driving means operated thereby. Thus, the motor is clamped in depending rela- 70 75

tion by clamp bolts 102 and nuts therefor to an adjustable motor mounting plate 103, shown as a pivoted plate provided with bearings 104, in which bearings and in bearings 105 on the top or plate 24, a pivot rod 106 is located for pivotally supporting the mounting plate for the motor, the pivot rod being held in axial direction by a set bolt 107 threaded in one of said bearings. A threaded stud 108 is fixed in the plate 24 and extends through a hole in the motor plate. Nuts threaded about said stud at opposite faces of said motor plate adjust the motor plate and clamp the same in adjusted positions, regardless of the position of the motor with relation to the feed wheel, that is, whether the motor is below, above or to either side of the position of the feed wheel, or regardless of the direction in which the frame extends from its support, whether that support be the table, an overhead support, or a wall or post.

A speed reducing device 115 is mounted on the top or plate 24 and is clamped in operative position by means of clamping bolts and nuts 116 therefor, the bolts passing through enlarged mating holes 117 in feet 118 of the frame of the speed reducing device, a washer 119 being located under the head of each of the bolts.

The rotor shaft 121 of the motor has a pulley 122 secured thereto, a flexible drive connection 123 being received thereabout and about a pulley 124 on a shaft 125 on the speed-reducing device 115 mounted on the frame. These pulleys are exemplified as sprocket wheels and the flexible connection is exemplified as a sprocket chain. Adjustment of the motor plate 103 adjusts the tension of the flexible drive connection.

The speed-reducing device is exemplified as comprising a separable frame 128 having a supporting member 129 secured to the frame in proper relation to the motor and the pulley which drives the same, the holes 117 being enlarged with relation to the clamping bolts 116 for permitting shifting of the speed reducing device on the frame and adjusting it with relation to the jaw pulling horn. The feed wheel 52 rotates at about 9 to 10 R. P. M.

The shaft 125 is exemplified as a worm shaft and is journaled in bearings 130, 131 in the supporting member of said speed reducing frame, and has a worm 132 fixed thereto, the hub of which has end contact with end thrust bearings 133, 134, shown as ball bearings, located between the ends of said hub and the inner ends of said bearings 130, 131, to endwise position the worm and its shaft.

A worm wheel 135 is fixed to the shaft 51 journaled in bearings 136, 137 in the frame 128. These bearings are shown as split bearings, the parts whereof are located respectively in the supporting member 129 and in a cap member 138, the cap member being secured to the supporting member by means of bolts 139 passing through holes in lugs 140 in said members and having clamp nuts 141 threaded to their threaded ends. The supporting member and the cap member have enveloping walls 142 for enclosing the worm and worm wheel.

The shaft 51 is shown as the feed shaft, and is held endwise by having the inner end of the hub of the feed wheel 52 coat with the bearing 48, and providing the shaft with a collar 143 fixed to said shaft by a set bolt 144 and coacting with the outer end of the bearing 136.

In operation, referring particularly to Figs. 1, 2, 4 and 6, the carcass head, after having had the

snout and skin, fat and meat in rear thereof pulled therefrom, and having had other trimming operations performed thereon after the snout pulling operation, as is usual in this industry, is fed mouth first over the horn, as by having the operator place the mouth end of the head about the infeeding end 70 of the horn, with the jaw presented upwardly and the skull portion of the head presented downwardly. The head is then pushed along the horn until it is contacted by a finger 58 of the rotating feed wheel 52, whereupon the carcass head is fed by said feed wheel along the tracks 69, 72, the feed fingers 58 contacting the jaw and the outer periphery of the feed wheel holding the jaw toward the track 69, the major portion of which is substantially concentric with said outer periphery. The fingers are of greater width than thickness, their width dimensions being parallel with their feeding paths for exerting great feeding force and imparting great feeding strength to said fingers. These fingers are also readily removable from and insertible in the wheel for repair and replacement of the same.

As the head is fed along the horn, the jaw and the skull portions thereof are relatively spread by the wedge form of the horn and the spreading and separating relation between the track 69 and the coacting tracks 72 for separation between the jaw and the skull, the jaw being fed along the track 69 of the horn by the feed fingers to the outfeeding end thereof and the skull dropping or being removed from the outer face of the horn for further operations on the jaw and the skull. The severed jaw is of substantially U-form, its front forming a cross member which rests on the horn, and the sides or jaw bones arranging themselves by gravity at the respective sides of the horn. The jaws may drop or be removed from the outfeeding end of the horn, or they may be fed along an outfeeding rod (Figs. 3 and 6), extending from the outfeeding end of the horn. If desired, the connecting gristle and muscles of the joint between the jaw and the skull may be severed or chiseled for more ready separation of the same while passing along the horn.

The stripper 81 is provided at the outfeeding end of the horn and coacts with the feed fingers for ready release of the severed jaws from said fingers.

The horn, the stripper, the feeding space and the feed wheel are arranged to project or overhang laterally from the frame and the pedestal thereof at one side of the frame, providing free space under, above and at the front and rear thereof for unobstructed placement, feeding and delivery of the head and its severed jaw and skull. The feeding space between the walls 42 and 91 is preferably open at the outer margins 60 of said walls for ready access into the interior of said space, making all parts thereof readily accessible.

The frame is constructed to project in various directions from supports; the horn, stripper and connecting means between the walls are readily adjustable about the axis of the feed wheel; the horn and the stripper are arranged to be projected in different directions; and the direction of rotation of the feed wheel is reversible, to adjust the horn and stripper into most convenient positions and directions of operation and for rotating the feed wheel in most desirable direction according to the direction in which the frame projects and the most desirable direction

of feeding movement of the carcass head, making my improved device extremely adaptable for most desirable, convenient and economical operation and for most desirable positioning of the same with relation to the positions of operatives and the desired positioning and passage of the carcass heads and their severed jaw and skull, and the parts to be severed therefrom.

The feet 35 of the frame are provided with 10 holes 33 through which suitable lag screws 34 pass into the support for the frame. This support may be the table 37, from which the frame projects upwardly, as exemplified in Figs. 8 and 9. The support may be an overhead ceiling or framing 15 151, from which the frame of the machine depends, as exemplified in Figs. 10 and 11. The support may be an upright wall or post 152, from which the machine frame projects laterally, as exemplified in Figs. 12, 13, 14 and 15, the frame 20 projecting toward the right in Figs. 12 and 13, and toward the left in Figs. 14 and 15. The direction in which the feed wheel desirably rotates is exemplified by an arrow in each of the Figs. 8 to 15, and the desirable direction in which 25 the horn and the stripper respectively project is shown in each of these figures.

It will be noted that in each instance there is free space under the horn, the stripper, the feed wheel and the feeding space for freedom of movement by the operator of the machine and for other operatives adjacent thereto for convenient and speedy manipulation of the carcass head and its severed parts and for trimming of the same.

35 Referring to Figs. 6 and 7, the walls 42 and 91 are provided with mating holes for suitable fastening means for the horn, the stripper and the connecting and spacing means in the various positions and directions of projection and operation 40 of my improved device. The desired direction of feeding movement of the feed wheel is desirably obtained by providing a reversible electric motor as the power applying means.

The inner wall 42 is exemplified as provided 45 with four groups *a*, *b*, *c*, *d* of equally spaced holes, these groups of holes being at the respective right angular dimensions of the margin of the inner wall at substantially right angles to the frame. Each group comprises an outer set 50 of two holes and an inner set of three holes centrally positioned with relation to said right angular dimensions. The holes of the outer sets are designated respectively *a*1, *a*2; *b*1, *b*2; *c*1, *c*2; and *d*1, *d*2. The holes of the inner sets are designated respectively *a*3, *a*4, *a*5; *b*3, *b*4; *c*3, *c*4, *c*5; and *d*3, *d*4, *d*5. The holes of the outer sets are preferably located respectively in radially extending lips *k*, *l*, *m*, *n*.

The outer wall is preferably of a form similar 60 to the form of the inner wall, but I prefer to rotatively adjust the outer wall with relation to the inner wall, whereby most of the holes which would otherwise register with the holes in the inner walls and two of the radially extending lips 65 may be dispensed with, and all of the holes in the outer wall will at all times be filled with fastening means to avoid leakage through the outer wall.

Thus the outer wall (see Fig. 7) may be provided with four groups of holes *e*, *f*, *g* and *h*, at right angular dimensions thereof. The group *e* comprises an outer set of two holes *e*1, *e*2; group *f* comprises an inner hole *f*8; group *g* comprises an outer set of two holes *g*1, *g*2; and group *h* 75 comprises an inner hole *h*4. The outer holes

mentioned are at greater distance from the axis of said outer wall than said inner holes, to correspond with the positions of the respective mating outer holes and inner holes having similar exponents in the inner wall 42. The outer holes in the outer wall register with given ones of the respective outer holes in the inner wall, and the inner holes in the outer wall register with selective ones of the inner holes in the inner wall.

By this arrangement all of the holes in the outer wall will be filled by securing means in assembling the parts, and the outer wall may be adjusted about the axis of rotation of the feed wheel so as to locate the outer wall in such angular position as may be desired or advisable according to the direction in which the frame of the machine is projected from its support, whether upwardly or downwardly or laterally in either direction, and the direction in which it is desired to feed the carcass heads. The outer sets of holes are located in oppositely projecting lips *o*, *p*, which are adapted to be registered with opposite ones of the respective pairs of lips in the inner wall to locate the outer wall in selective right angular positions.

When my improved device is positioned in upright position with the infeeding end of the horn at the left and the stripper at the right, as shown in Fig. 8, the bolts for the horn are in the holes *c*1 and *c*2 in the inner wall and in the holes *g*1 and *g*2 in the outer wall, and the bolts for the stripper are in the holes *b*4 and *b*5 in the inner wall and in the hole *f*4 in the outer wall, there being only one bolt connecting the outer flange of the stripper with the outer wall, which has been found sufficient for rigidly connecting the walls and stripper. The upper connecting bolts for the walls are in the holes *a*1 and *a*2 in the inner wall and in the holes *e*1, *e*2 in the outer wall. The left-hand connecting bolt is in the hole *d*4 in the inner wall and in the hole *h*4 in the outer wall, and the right-hand connecting bolt is omitted as the walls at this side are held in correct rigid relation by the stripper and its bolts.

When my improved device is positioned in upright position with the infeeding end of the horn at the right and the stripper at the left, as shown in Fig. 9, the positions of the securing bolts and connecting bolts are as explained in connection with Fig. 8, except that the direction in which the horn projects is reversed, and the bolts for the stripper are in the holes *d*3, *d*4 in the inner wall and in the hole *h*4 in the outer wall, the connecting bolt at that side being omitted, and the connecting bolt being placed at the right side of the walls and located in the hole *b*4 in the inner wall and in the hole *f*4 in the outer wall.

When my improved device is in depending position with the infeeding end of the horn at the left and the stripper at the right, as shown in Fig. 10, the walls are in upside down relation and the bolts for the horn are in the holes *a*1, *a*2 in the inner wall and in the holes *e*1, *e*2 in the outer wall, and the bolts for the stripper are in the holes *d*4, *d*5 in the inner wall and in the hole *h*4 in the outer wall. The end connecting bolts for the walls which are in this arrangement adjacent to the frame, are in the holes *c*1, *c*2 in the inner wall, and in the holes *g*1, *g*2 in the outer wall. The left connecting bolt is in the hole *b*4 in the inner wall and in the hole *f*4 in the outer wall, the right connecting bolt being omitted on account of the connection of the walls by the 75

stripper and its bolts then located at the right side of the wall.

When my improved device is in depending position with the infeeding end of the horn at the right and the stripper at the left, as shown in Fig. 11, the securing bolts and the connecting bolts are as shown in Fig. 10, except that the horn is reversed so that its infeeding end is projected toward the right and the bolts for the stripper are located in the holes $b3$, $b4$ in the inner wall and in the hole $f4$ in the outer wall, the left connecting bolt being omitted, and the right connecting bolt being in the hole $d4$ in the inner wall and the hole $h4$ in the outer wall.

15. When my improved device is positioned so as to project laterally toward the right with the infeeding end of the horn at the left and the stripper at the right, as shown in Fig. 12, the position of the outer wall is changed angularly about the axis of the feed wheel so that its outer sets of holes are at the top and bottom of the wall and the inner holes are at the sides of the wall, at right angles to the frame, locating the outer wall in upright relation similar to its location when the device is projected upwardly or downwardly, but rotated in counterclockwise direction at an angle of ninety degrees with relation to the frame.

In this adjusted position of the device and its parts, the bolts for the horn are in the holes $b1$, $b2$ in the inner wall and in the holes $g1$, $g2$ in the outer wall, and the bolts for the stripper are in the holes $a4$, $a5$ in the inner wall and in the hole $f4$ in the outer wall. The upper connecting bolts are in the holes $d1$, $d2$ in the inner wall and in the holes $e1$, $e2$ in the outer wall, and the left connecting bolt for the walls is in the hole $c4$ in the inner wall and in the hole $h4$ in the outer wall, the right hand connecting bolt being omitted.

40. It will be noted that when the device is projected in lateral direction, the direction of projection of the inner wall from the frame remains the same relatively to the frame as when the device is in upright position or in depending position, the outer wall being, however, rotated angularly throughout an angle of ninety degrees about the axis of rotation of the feed wheel, the direction of rotation exemplified in the present instance being counterclockwise.

50. When my improved device is in laterally extending position toward the right with the infeeding end of the horn projecting toward the right, as exemplified in Fig. 13, the locations of the securing bolts and connecting bolts are the same as described in relation to the device shown in Fig. 12, except that the horn is reversed, and the bolts for the stripper are in the holes $c3$, $c4$ in the inner wall and in the hole $h4$ in the outer wall, the connecting bolt at the left being omitted, and the connecting bolt at the right being located in the hole $a4$ in the inner wall and in the hole $f4$ in the outer wall.

When my improved device is in laterally extending position toward the left, with the infeeding end of the horn projecting toward the left, as shown in Fig. 14, the outer wall is again in angular position with relation to the frame, being rotated throughout an angle of ninety degrees either to the right or to the left as compared with the upright position or depending position of the device. In such relation, assuming that the outer wall has been rotated clockwise with relation to the inner wall, the bolts for the horn are in the holes $d1$, $d2$ of the inner wall and in the holes $g1$, $g2$ in the outer wall, and the bolts for the stripper are in

the holes $c4$, $c5$ in the inner wall and in the hole $f4$ in the outer wall. The upper connecting bolts are in the holes $b1$, $b2$ in the inner wall and in the holes $e1$, $e2$ in the outer wall, the left connecting bolt being in the hole $a4$ in the inner wall and in the hole $h4$ in the outer wall, the right connecting bolt being omitted.

When my improved device is in laterally extending relation toward the left, with the infeeding end of the horn toward the right, as shown in Fig. 15, the securing bolts and connecting bolts are in the positions described in Fig. 14, with the exception that the horn is reversed, the bolts for the stripper are located in the holes $a3$, $a4$ in the inner wall and the hole $h4$ in the outer wall, the connecting bolt at the left side of the walls being omitted, and the connecting bolt at the right being in the hole $c4$ in the inner wall and in the hole $f4$ in the outer wall.

20. My improved device provides simple, convenient and strong means for pulling the jaws of carcass heads, enables the feeding to be accomplished with extreme freedom and certainty, enables my improved device to be selectively adjusted, arranged and placed for most convenient 25 operation in various locations and in most convenient positions with relation to the stations of other operatives and for prior and subsequent operations upon the carcass head and its parts.

I claim:

1. In a jaw puller, the combination of a frame arranged to be secured to supports so as to project selectively in various directions, said frame having a feeding space located laterally outwardly from said frame, a feed wheel rotatable in said feeding space, a jaw pulling horn and a jaw stripper coacting with said feed wheel, and means for adjustably positioning said jaw pulling horn and said jaw stripper into various angular positions about said feed wheel so as to coact with 40 said feed wheel to conform to the selective direction in which said frame projects.

2. In a jaw puller, the combination of a frame arranged to be secured to supports so as to project selectively in various directions, an inner wall and an exposed outer wall having a feeding space therebetween located laterally outwardly from said frame, a feed wheel rotatable in said feeding space, a jaw pulling horn and a jaw stripper coacting with said feed wheel and securing means between said walls and between said walls and said jaw pulling horn and said jaw stripper; said exposed outer wall, said jaw pulling horn, said jaw stripper and said securing means being adjustable about the axis of said feed wheel so as to secure the same in various angular positions about said axis to conform to the selective direction in which said frame projects.

3. A jaw puller comprising a frame provided with securing means at one end thereof to secure said frame to supports so as to project in various selective directions therefrom, a pedestal on said frame, a feed wheel journaled in said pedestal, a jaw pulling horn with which said feed wheel coacts to pull jaws, and securing means between said horn and said pedestal at a plurality of angular positions about the axis of rotation of said feed wheel whereby to place said horn under said feed wheel during selective secured connection of said one end of said frame 70 to project said frame in said respective selected directions.

4. A jaw puller comprising a supporting frame arranged to be positioned in various directions from supports, a pedestal extending therefrom at 75

- one side thereof and having a substantially annular margin to form an inner wall of a feeding space, an outer wall for said feeding space having an outer substantially annular margin substantially concentric with and spaced outwardly from said inner wall to form said feeding space substantially annular and overhanging laterally from said frame, a feed wheel in said feeding space substantially concentric with and between said walls and overhanging from said frame, a jaw pulling horn overhanging laterally from said frame and having a jaw riding face in said space substantially concentric with said feed wheel and provided with an infeeding end extending outwardly in the plane of said space and beyond said walls, and means for selectively securing said horn at various angular positions about the axis of said feed wheel to place said horn under said feed wheel throughout the various positions of said frame.
5. In a jaw puller, the combination of a frame, a pedestal extending therefrom at one side thereof and forming the inner wall of a feeding space, an outer wall for said feeding space, said outer wall overhanging laterally from said frame, a feed wheel located outwardly from said frame in said feeding space, said feed wheel being rotatable selectively in opposite directions according to the desired direction of feed of jaws being pulled, a jaw pulling horn with which said feed wheel coacts having an infeeding projection and an outfeeding end, a stripper for the feed wheel at said outfeeding end, means to secure said frame to a support to project in various directions from said support, and means to secure said jaw pulling horn and said stripper in various angular positions and so as to extend selectively in opposite directions between said walls about the axis of rotation of said feed wheel with said infeeding projection extending in selective directions according to the desired direction of projection of said frame and the desired direction of feed of jaws being pulled.
6. In a jaw puller, the combination of a frame, a wall of a feeding space thereon, said wall having a margin provided with radially projecting lips at substantially right angular dimensions thereof at substantially right angles to said frame to form two pairs of oppositely extending lips, an opposite wall of said feeding space having a margin provided with radially projecting lips at diametrically opposite dimensions thereof corresponding with selective ones of said right angular dimensions, said opposite wall being adjustable on its axis about the axis of said first-named wall to locate the lips of said opposite wall in registry with selective ones of said pairs of lips of said first-named wall, a feed wheel in said feeding space, a jaw pulling horn and a stripper with which said feed wheel coacts, securing means whereby to secure said horn in selective opposite directions between a selective one of said lips of said opposite wall and a selective one of said oppositely extending lips of a selective one of said pairs of oppositely extending lips, and

securing means inside the cylindrical projection in which said first-named securing means are located having the axis of rotation of said feed wheel as its center to secure said stripper in selective opposite directions between said walls. 5

7. In a jaw puller, the combination of a frame arranged to be secured to supports so as to project selectively in various directions, a pair of walls on said frame having a feeding space therebetween, a feed wheel rotatable in said feeding space, a jaw pulling horn and a jaw stripper between said walls coacting with said feed wheel, and means for positioning said jaw pulling horn and said jaw stripper in various angular positions between said walls about said feed wheel so as to coat with said feed wheel to conform to the selective direction in which said frame projects.

8. In a jaw puller, the combination of a frame, a wall of a feeding space thereon, said wall having a margin provided with radially projecting lips at substantially right angular dimensions thereof to form two pairs of oppositely extending lips, an opposite wall of said feeding space having a margin provided with radially projecting lips at diametrically opposite dimensions thereof corresponding with selective ones of said right angular dimensions, one of said walls being adjustable on its axis about the axis of the other of said walls to locate the lips of said opposite wall and the lips of a selective one of said pairs of lips of said first-named wall in registry with each other, a feed wheel in said feeding space, a jaw pulling horn and a stripper with which said feed wheel coacts, securing means whereby to secure said horn in selective opposite directions between selective ones of said lips of said walls, and securing means to secure said stripper in selective opposite directions between said walls in selectively coercive relations with said horn when secured in such selective opposite directions. 35

9. In a jaw puller, the combination of a supporting frame, an inner wall and an outer wall on said supporting frame having a feeding space therebetween to form a feeding structure which overhangs said supporting frame at said walls to provide free space thereunder at the side of said supporting frame, a feed wheel provided with feeding fingers and rotatable in said feeding space, a jaw pulling horn comprising an inner track substantially concentric with the feeding path of said rotary feed wheel with which said feed wheel coacts and with outer tracks to separate the jaw from the skull portion of the head being operated on, and a jaw stripper secured between said walls and provided with stripper fingers having contact faces projecting inwardly and tangentially to the feeding path of said feeding fingers and at the respective sides of said feeding fingers and between which said feeding fingers move for stripping pulled jaws from said feeding fingers, and constructed to release the skull portions of said heads in said free space at the side of said supporting frame. 50
